[57] CLAIM

The ornamental design for a hand grip, as shown and described.

DESCRIPTION

FIG. 1 is a perspective view of a hand grip showing my new design thereof;

FIG. 2 is a front elevational view and the rear elevational view being a mirror image of FIG. 1;

FIG. 3 is a left side elevational view and right side elevational view being a mirror image of FIG. 1;

FIG. 4 is a top plan view of FIG. 1;

FIG. 5 is a bottom plan view of FIG. 1; and,

FIG. 6 is a reduced perspective view of FIG. 1, with the broken line showing of a suitcase being for illustrative purposes only and forming no part of the claimed design.
